UNITED STATES PATENT OFFICE.

JAMES C. LAWRENCE, OF WEST ASHEVILLE, NORTH CAROLINA.

BRACE FOR MILLING-MACHINES.

1,342,390.

Specification of Letters Patent.

Patented June 1, 1920.

Application filed June 17, 1919. Serial No. 304,864.

To all whom it may concern:

Be it known that I, JAMES C. LAWRENCE, a citizen of the United States, residing at West Asheville, in the county of Buncombe 5 and State of North Carolina, have invented new and useful Improvements in Braces for Milling-Machines, of which the following is a specification.

This invention relates to improvements 10 in braces for milling machines, in the use of which the usual vibration and chatter incident to cutting large gears is entirely avoided.

The improved brace member comprises a 15 vibrating bar pivotally mounted upon an upright extending from the base and capable of being put under tension, the end of the bar being engaged when off center with the underside of the gear being cut. Any liability of vibration of such gear is counteracted to an appreciable extent by the brace 20 incident to the fact that it is itself off center and held under spring tension.

In the drawings:—

25 Figure 1 is a view illustrating the application of the improved brace.

Fig. 2 is an enlarged vertical elevation of the brace detached.

30 Figs. 3, 4, 5, 6, 7 and 8 are respective views in elevation, showing the slightly modified forms of the brace.

The brace proper comprises a base 1 formed with an opening 2 by which said brace may be bolted in place when desired, 35 and an upright 3 rising from the base. Pivotally mounted in the upright 3 is an L-shaped vibrating member 4 comprising an approximately vertical rod 5 and a lateral arm 6. The terminal of the rod 5 is threaded 40 to receive an adjusting screw 7 having a rounded head 8, and the arm 6 has a screw threaded therethrough carrying on the lower end a disk 9 between which and the base is arranged a coil spring 10.

45 In operation, the brace is positioned as illustrated in Fig. 1, that is, the base is arranged upon the machine and the head 8 of the adjusting screw positioned beneath the gear being cut as at 11. The upright bar 50 is adjusted slightly off center, prior to its engagement with the gear being cut, that is out of vertical alinement with the upright 3 so that the slightest tendency to vibration in the gear lever will be counteracted by the 55 spring pressed member 4.

In Fig. 3 a base 12, upright 13, and vibrat-

ing member 14 are similar to the parts previously described, except that the lateral arm 15 thereof is terminally provided with a hook 16, to which one end of a coil spring 17 is secured. The opposite end of this spring is secured to a similar hook 18 arranged above the arm 15 and carried in a supporting upright 19 secured on the base.

In Fig. 3 the operation is as previously described though in this instance the hook 18 is mounted for adjustment in order to arrange the vibrating portion or member off center as described in connection with the preferred construction.

In Fig. 4 the device comprises a base 20 from which rises an upright 21 carrying a vibrating rod 22 pivotally secured thereto. A similar upright 23 rises from the base and the vibrating rod 22 and upright 23 are provided with spring receiving members 24 between which the coil spring is adapted to be positioned. The member 24 on the upright 23 is mounted for adjustment through the screw 25, whereby the spring may be 70 adjusted to give the desired off center position to the vibrating rod 22.

In Fig. 5 is the device shown as comprising a base mounted at 26 carrying a spring hook 27 and an upright 28. To the upright 85 is pivoted the L-shaped vibrating rod 29 and the short arm 30 carries an adjustable spring hook 31. A spring is secured between the hooks 27 and 31 whereby the vibrating rod may be adjusted off center as is necessary 90 in use.

In Fig. 6 the base is shown at 32 and is provided with uprights 33 and 34. A vibrating rod 35 is pivotally mounted in the uprights 33 and said rod and the upright 34 95 are provided with bowed hooks 36 and 37 to receive the springs between them. The hook 37 is adjustable in the upright 34, for the purpose previously mentioned.

In Fig. 7, the device is shown as comprising a base 38, from which rises an upright 39. The upright has a lateral projection 40 from which extends a hook 41, and the vibrating rod 42 is pivotally mounted in the upper end of the upright 39. The rod 105 42 is provided with a lateral arm 43 having a spring hook 44 adjustably mounted thereon. The spring whereby the operating rod may be held off center for use is connected between the hooks 41 and 44 as 110 will be apparent.

In Fig. 8 the device is shown as compris-

ing a base 45 from which rises an upright 46 and in the upper end of which upright is mounted the usual vibrating rod 47. A leaf spring 48 is secured upon the rod 49 extending through the vibrating rod 47 and bears at its free end upon the upright 46. The tension of the connected end of the leaf spring is adapted to be adjusted through a nut 50 whereby the vibrating rod may be thrown off center as is necessary in use.

It will be apparent in all forms described that the vibrating rod or the rod adapted to engage the gear is adjustable off center and held so through a medium of a spring member which spring member resists the return of said rod to a vertical position, and in such resistance tends to overcome the vibration of the gear or other article with which the rod is engaged. This will prevent vibration of the gear and the chattering of the work during the milling operation.

Having thus described the invention what is claimed is:—

1. A brace for milling machines comprising a base, an upright rising therefrom, a vibrating rod pivotally mounted in the upright and having an end adjustable to an adjacent article and spring means for holding said upright rod offset from the vertical. 25

2. A brace for milling machines comprising a base, an upright rising therefrom, a vibrating rod pivotally mounted in the upright, an article engaging member adjustably mounted in the end of the vibrating rod, a spring and means for adjusting the tension of the spring with respect to the vibrating rod, whereby said rod may be arranged out of vertical alignment with the upright as and for the purpose described. 30

In testimony whereof I affix my signature. 35

JAMES C. LAWRENCE.
